Specification for Design.

Patented Nov. 22, 1921.

Application filed August 29, 1921. Serial No. 496,721. Term of patent 14 years.

To all whom it may concern:

Be it known that I, WILLIAM S. FINLEY, a citizen of the United States, residing at Cleveland Heights, in the county of Cuyahoga and State of Ohio, have invented a new, original, and ornamental Design for a Saving-Bank, of which the following is a specification, reference being had to the accompanying drawing, forming part thereof.

In the drawing Figure 1 is a front elevation and Fig. 2 is a side elevation of a savings bank, showing my new design.

I claim:

The ornamental design for a savings bank, as shown.

WILLIAM S. FINLEY.
